UNITED STATES PATENT OFFICE.

JOHN M. LINE, OF SPRINGFIELD, MISSOURI.

FOLDING BED OR COT.

Application filed September 17, 1924. Serial No. 738,177.

To all whom it may concern:

Be it known that I, JOHN M. LINE, a citizen of the United States, residing at Springfield, in the county of Greene and State of Missouri, have invented certain new and useful Improvements in Folding Beds or Cots, of which the following is a specification.

My invention relates to improvements in folding beds or cots, of the type shown in Letters Patent No. 1,492,254, granted to me under date of April 29, 1924.

An important object of the invention is to provide simple and reliable means, whereby the effective length of the transverse supporting bars, may be varied, to fit automobiles of different sizes.

A further object of the invention is to improve the construction of the folding legs of the cot or bed, with the view of simplifying and strengthening the same, and rendering it easier to attach the same to the longitudinal suspension bars of the device.

A further object of the invention is to provide improved and simplified means for holding the bottom of the bed taut.

Other objects and advantages of the invention will be apparent during the course of the following description.

In the accompanying drawings forming a part of this specification and in which like numerals are employed to designate like parts throughout the same,

Figure 1 is a side elevation of a cot or bed embodying my invention, showing the same in use,

Figure 2 is an end elevation of the same,

Figure 3 is a bottom plan view of one of the supporting members,

Figure 4 is an end elevation of the same, and,

Figure 5 is a perspective view of one of the legs.

In the drawings wherein for the purpose of illustration is shown a preferred embodiment of my invention, the numeral 10 designates a pair of transverse supporting members, which are identical. Each supporting member embodies a transverse bar or beam, preferably formed in two sections 11, which are hinged together, at their inner ends, at 12, whereby the outer ends of the beam sections 11 may swing downwardly below the horizontal, but cannot swing upwardly beyond the same.

In order that the length of the transverse beam may be varied, I provide extension feet or elements 12' disposed near and beneath the outer ends of the beam sections 11, as shown. The feet 12' have pivotal connection at 13, with links or straps 14, the upper ends of which are pivoted to the beam extension 11, as indicated at 15. It is thus apparent that the extension feet 12', are permanently attached to the beam sections 11, and may be swung longitudinally of the same, to inner or outer positions, as shown.

The numeral 16 designates folding legs, which are inverted U-shaped in cross section. The base of these legs is cut away, near and spaced from their lower ends, providing knuckles 17, arranged upon opposite sides of the beam sections 11, and pivotally connected therewith, as shown at 18. At their upper ends, the bases of these legs extend to the free ends of the same, and have notches 17', for the reception of bolts 18', which are carried by longitudinal beams 19. These beams have the bottom 20, attached thereto, by any suitable means. It is thus seen that a very strong and convenient connection is effected between the outer ends of the legs 16, and the beams 19, and as the beams 19 tend to move inwardly upon these legs, it is not necessary that the bolts 18' have clamping engagement with the legs, but it is sufficient that the bolts be simply inserted in the notches 17'. This provides a construction which will permit of the convenient and ready separation of the beams 19 and the legs.

The numeral 21 designates flexible elements in the form of a chain, having flat links. The upper ends of these chains are attached to the beams 19, while selected links are adapted to be inserted upon pins 22, which are attached to the ends of the beam sections 11, as shown.

In the use of the device, the transverse bars are arranged upon the tops of the sides of the automobile, and the bed or cot is supported within the top of the automobile, as clearly shown in Figure 1. It is obvious that the longitudinal beams 19 and top 20 may be readily separated from the legs 16, and the bottom 20 rolled about these beams. The legs 16 may be folded down upon the beam sections 11, which in turn may be folded transversely upon themselves.

It is to be understood that the form of my invention herewith shown and described, is to be taken as a preferred example of the same, and that various changes in the shape, size, and arrangement of parts, may be resorted to without departing from the spirit of my invention or the scope of the subjoined claims.

Having thus described my invention, I claim:

1. In a cot or bed for use in connection with an automobile comprising a pair of transverse bars to be supported above the upper edge of the body of the automobile, extension feet arranged beneath and adjacent to the ends of said bars, a pair of links pivotally connected with each of the extension feet and pivotally connected with the adjacent end of the transverse bar, said feet being movable from one position to another in facial abutment with the transverse bars and adapted, when projected, to extend beyond the outer terminals of the transverse

members, legs carried by the transverse bars, and a bottom supported by said legs.

2. A bed or cot for use in connection with an automobile or the like comprising transverse bars, legs arranged above said bars, each leg being inverted U-shaped in section providing opposed flange members and an intermediate web portion, the flange members at one end of each leg being extended and snugly embracing the transverse bar, means pivotally connecting the extended flange members of the legs to the transverse members, longitudinal bars, a bottom carried by the longitudinal bars, said longitudinal bars lying in engagement with the web portions of the legs at the opposite ends of the latter, headed bolts carried by the longitudinal bars, the web portions of the legs having slots therein detachably receiving said bolt, and adjustable means connecting the longitudinal bars with said legs.

In testimony whereof I affix my signature.
JOHN M. LINE.
